CLAES RYDEN, OF PROVIDENCE, RHODE ISLAND, ASSIGNOR TO UNIVERSAL WINDING COMPANY, OF PORTLAND, MAINE, A CORPORATION OF MAINE.

WINDING-MACHINE.

1,138,320.

Specification of Letters Patent.

Patented May 4, 1915.

Application filed June 26, 1912. Serial No. 706,063.

To all whom it may concern:

Be it known that I, CLAES RYDEN, a citizen of the United States, residing at Providence, in the county of Providence and State of Rhode Island, have invented certain new and useful Improvements in Winding-Machines, of which the following is a specification.

My invention relates to winding machines for winding thread and yarn into cops, bobbins or other forms of packages.

My invention consists particularly of improvements in the structure and arrangement of the mechanism of the machine whereby its efficiency is increased and its operation simplified.

The invention is fully described in the following specification, illustrated by the accompanying drawings, in which:

20 Figure 1 is a front elevation of one unit or "head" of my improved machine arranged for winding cops at both ends of the winding-spindle, but with the winding mechanism shown at one end only. Fig. 2, 25 an end elevation of the same; Fig. 3, a similar elevation, with the mechanism shown part-sectional on the line X—X of Fig. 1; Fig. 4, a longitudinally-sectional view of the spindle clutch-device; Fig. 5, a plan view 30 of the same; Figs. 6 and 7, detail views of the thread-guide and traverse mechanism; Fig. 8, a sectional view of the traverse-frame dog and sector taken on the line Z—Z, Fig. 2.

35 My new machine is intended to be built in "gangs" or series of any suitable number of units or heads, but as all of the heads are of the same design and structure it has been considered sufficient to illustrate and 40 describe only one. Furthermore, as both ends of each head are substantially the same in construction and arrangement the parts at one end are not shown in Fig. 1 and need not be here described except to state that 45 they operate in the same manner as that of the mechanism explained.

Referring first to Fig. 1, the main frame A of the machine consists of the base a and two side-members or uprights a', a', joined 50 at the top by an arch or bridge-piece a². The side-members a', a' are formed with bearings a³, a³ for the horizontally arranged winding-spindle B and the base a has an upwardly projecting bearing a⁴ for the horizontal rock-shaft C which extends at right

angles to the spindle B. As usually arranged, the rock-shaft C extends the whole length of the bed or table which supports the several units or heads and is operated by a cam or other suitable device, not here 60 shown or described. Suffice it to say that one rocker-shaft serves for the traverse-motion of the whole series of heads and the oscillating motion may be imparted to the shaft in any convenient manner as now well 65 known in the art.

Mounted on the winding-spindle B is a driving-pulley B' which is secured to the spindle by the set-screw b. The pulley B' is driven from a driving belt, not here 70 shown, preferably arranged to connect the pulleys of all of the heads or units to a common source of power, such, for instance, as the driving-pulley of a motor or other prime-mover.

75 The side-members a', a' of the frame A are formed with forwardly projecting ears a⁵, a⁵, see Fig. 3, bored to receive a rod D which extends across the frame and projects therefrom at both ends. The rod D is secured in the ears a⁵, a⁵ by set-screws d, d, and carries at its front end a bracket E held thereon by the set-screw e. The bracket E is formed with an arm or elbow e' at the top of which is a bearing e². Mounted to rotate in the bearing e² is a live-spindle e³ which serves as a support for the outer end 80 of the cop-tube x, illustrated by dot-and-dash lines in Fig. 1. The spindle or cop-tube-support e³ is preferably mounted in a 85 sleeve or bushing e⁴ which is adapted to slide in the bearing e² against the action of a spring, not here shown. This arrangement provides for the retraction of the spindle so that the cop-tube may be placed in 90 position thereon with its opposite end supported on the cop-driver F, but as similar devices are well known in the winding-machine art, the mechanism is not here explained or illustrated in detail.

95 The cop-driver F which acts to support one end of the cop-tube x and also serves to drive the latter, is mounted in the end of the winding-spindle B and is connected to rotate therewith by means of a clutch-device 105 shown in detail in Figs. 4 and 5.

Referring to Fig. 4, the end of the spindle B is formed with an axial bore b' and is also provided with radial teeth b², see Fig. 5. The cop-driver F is fitted to the bore b' 110

and has a teat f with a beveled end bearing against the end of the bore b' . Mounted to slide on the cop-driver F is a clutch-member G in the form of a sleeve g, carrying a flange 5 g' at one end. The opposite end of the sleeve g is formed with teeth g^2 adapted to engage the teeth b^2 on the spindle B. A pin g^3 extends through the cop-driver F with its ends engaging a slot g^4 in the sleeve of the 10 clutch-member G to secure the latter rotatively with the cop-driver while allowing it to slide longitudinally thereon. The outer end of the cop-driver F is supported in a ball-bearing H which is held in a bracket h, 15 the latter extending up from the rod D and held in place thereon by a set-screw h' , see Figs. 1 and 2.

The cop-driver F is formed with a flange f' which acts as a retainer for holding the 20 balls h^2 in the bearing H and also takes the thrust of a saucer-shaped spring I arranged between the flange and the clutch-member G, see Fig. 4. Normally the spring I tends to maintain the clutch-member with its teeth in 25 engagement with those on the end of the spindle B so that the spindle and cop-driver rotate as one. The inner face of the flange g' on the clutch-member G is beveled at g^5 , and adapted to engage therewith is an oppo- 30 sitely beveled face j' of the clutch-lever J more fully described hereinafter. The end of the cop-driver F has a reduced portion f^2 adapted to enter the bore of the cop-tube α and a spline or key f^3 engages a slot in the 35 end of the tube to rotate the latter, the arrangement being the same as generally used on machines of this type.

Projecting outwardly from a boss or hub a^6 on the side-member a' of the frame A is a 40 rod K secured in position by the set-screw k . Mounted on the outer end of the rod K is a bracket K', held by the set-screw k' , and formed with the upwardly projecting arm k^2 terminating in a hub or bearing k^3 . 45 Mounted in the bearing k^3 is a horizontal rod L, secured by the set-screw l , and extending through an ear a^7 on the frame A, see Fig. 3. The rod L supports the traverse-frame M, which controls the thread-guide N, 50 and also serves as a track for the guide-holder as the latter is reciprocated back and forth along the winding-spindle. The frame M is preferably formed with two legs m and m' , see Figs. 1, 2 and 3, bored to receive the rod L on which the frame pivots. The upper portion of the frame consists of the back m^2 formed with a curved top portion or cowl r^3 , at either end of which are two ears m^4 , m^4 . Mounted between the ears 55 m^4 , m^4 , is a swinging bail O which is provided with pivot-pins or trunnions o , o engaging suitable holes in the ears. The bail O normally hangs in the position illustrated in Figs. 2 and 3 and is operated by means 60 later described to swing outward into the

position shown in Fig. 6 to carry the yarn out of the notch in the thread-guide for the purpose hereinafter explained. The frame M is also provided near its upper edge with two ears m^5 , m^5 , arranged at either end, and 70 through which extends a rod P. The rod P carries the dogging-lever S for the traverse-frame to control its swinging movement as later explained.

The thread-guide N consists of a button-shaped member n , preferably constructed of porcelain or other vitreous material, fastened to an angle-shaped support n' by the screw n^2 , see Figs. 1 and 6, and formed with a thread-notch or guide-slot n^3 on its upper 80 edge. The guide-support n' is secured in a thread-guide holder n^4 which is mounted to slide on the rod L as shown in Fig. 1. The guide-holder n^4 preferably takes the form of a bifurcated arm having its legs n^5 , n^5 curled 85 over to surround a sleeve n^6 which fits the rod L. At one end of the sleeve n^6 is a collar n^7 formed with the downwardly projecting ears n^8 , n^8 , between which is pivotally secured the end of a link q by means of 90 a screw or pin q' . As here shown the holder n^4 is secured on the sleeve n^6 against the collar n^7 by means of a split spring-ring n^9 sprung into a groove on the periphery of the sleeve. This arrangement allows the guide-holder to swing on the sleeve to adapt the thread-guide to move back away from the axis of the cop-tube as the yarn is built up 95 thereon. The upper portion of the guide-holder n^4 is formed with ears n^{10} , n^{10} , bent 100 around to form a slot adapted to receive the shank of the guide-support n' and the latter is secured therein by means of the screw n^{11} , see Fig. 6. The guide-support n' has a portion n^{12} adapted to bear on a raised face m^a 105 on the back of the traverse-frame M and also an upwardly extending finger n^{13} which is held in back of the rod P. By this means the thread-guide is adapted to slide in the traverse-frame M without swinging away 110 from the back of the latter and pressure exerted on the frame acts to resist the movement of the guide away from the axis of the cop-tube. Such pressure is usually provided by means of weights and I have here shown 115 a weighted arm M' fastened to the inner leg m' of the frame M by means of the screws m^7 , m^7 . The lower end of the arm M' is provided with a cavity m^8 from which projects a rod m^9 , and removable weights m^{10} 120 are secured on the rod by means of the collar m^{11} held by the set-screw m^{12} .

The thread-guide holder n^4 is reciprocated on the rod L by means of its connection, through the link q , to the oscillating lever 125 or rocker-arm Q. The arm Q is preferably formed of sheet-metal, to render it light in weight, and is secured to a crescent-shaped block q^2 , see Figs. 1 and 2, fastened to the rock-shaft C by the screw q^3 . The arm Q is 130

- provided with two series of holes q^4 , q^5 , etc., running its length and by adjusting the pin q^6 in these holes the operative length of the arm is altered to regulate the length of the 5 traverse of the thread-guide. It will be understood that the double series of holes in the arm provide for connecting the two thread-guides at the opposite ends of the winding-spindle.
- 19 It has been found advantageous in machines of this class to provide dogging means for checking the inward movement of the thread-guide, that is, its movement toward the axis of the cop-tube, after it has 15 once been forced out by the growth of the package. This prevents vibration or chattering of the guide and relieves the cop or package of undue pressure which would be liable to cause its ends to bulge.
- 20 In my present invention my improved dogging device is arranged as follows: Mounted on the rod D is a sickle-shaped arm R, which I term the dog-sector, formed with an arcuate portion r extending up 25 over the cop-driver F adjacent the side-member a' of the frame A. The hub r' of the sector R is secured to the rod D by a set-screw r^2 , see Fig. 3, and reaching down from the main portion of the sector is a 30 web extension r^3 formed with a hub r^4 adapted to surround a boss a^8 which projects from the frame A. The arcuate portion r of the sector R is provided with a tapered groove r^5 , see Fig. 8, the bottom of 35 which is formed concentric with the axis of the rod L on which the traverse-frame M swings. Secured to the rod P which is pivoted in the frame M, as before explained, is the dogging-lever S arranged at one side 40 of the frame and formed with an arcuate extension or shoe s adapted to engage the groove r^5 in the dog-sector R. The shoe s has its sides tapered to correspond with the taper of the groove r^5 , as illustrated in Fig. 45 8, so that when the shoe is forced into the groove it binds therein and prevents the frame M from swinging toward the axis of the cop-tube. It will also be noted that the form of the dogging-lever S is such that 50 pressure on the traverse-frame in the opposite direction, that is, tending to carry the frame away from the cop-tube, will act to relieve the frictional engagement of the shoe s with the sector R, so that the movement 55 of the frame in this direction is not resisted by the dogging-lever. The lever or dog S is controlled by a finger-lever S' secured to the opposite end of the rod P. This is 60 preferably formed of sheet-metal with a forked portion s' clamped to the rod P by the set-screw s^2 . A flat spring s^3 is secured to the back of the lever S' with its lower, curved end bearing against the back of the 65 traverse-frame M and tending to force the dog S into binding engagement with the
- sector R; while pressure on the lever in the opposite direction will release the dog from the sector and allow the frame to be adjusted manually to set the thread-guide close to the cop-tube at the start of the winding 70 operation.
- The clutch-lever J which operates the clutch-member G, as before explained, is formed with a hub j mounted on a horizontal rod T and secured in place by the 75 set-screw j^3 . The rod T extends parallel with the rod D, in front of the latter, and is supported therefrom by the two levers T' and U. The lever T' is pivoted at one end on the rod D and its opposite end surrounds 80 the rod T and is secured fixedly thereto by a set-screw t .
- Preferably, the rod T is milled down on one side at t' throughout approximately its whole length, so as to provide a flat bearing face for the ends of the set-screws which 85 secure the various levers, later described, firmly on the rod. The outer end of the rod T is bent down in the handle T² which serves to rock the rod T in an arc around 90 the rod D as a pivot. The lever U which helps to support the rod T is preferably formed of relatively thin sheet-metal, see Fig. 1, and like the lever T' is hinged on the rod D. Its rear end projects in the form 95 of an arm u terminating in a curved portion u' having an arcuate slot u^2 . Referring to Fig. 3, the slot u^2 is engaged by the bent end v of a wire member V which slides vertically in a bore m^{13} of the portion m^{14} of the traverse-frame M. The upper end of the member V is bent over at v' to adapt its forward end to engage a pin o' on the end of the thread-bail O. Normally the position of the lever U is such that the curved slot u^2 is concentric with the axis of the rod L so that as the 100 traverse-frame swings about this axis the position of the member V is not changed. When, however, the lever U is rocked upward under the action of the stopping 105 mechanism of the machine, as later described, the slot u^2 acts to lift the member V to cause its upper bent end v' to engage the pin o' and swing the bail forward into the position illustrated in Fig. 6. This rocking movement of the bail O lifts the thread or yarn y out of the notch n^3 in the thread-guide N so that the continued reciprocation of the latter, after the arrest of rotation of the cop, will not break or damage the yarn. 110
- 115 Mounted on the rod T, inside of the upright a' of the frame A, is an arm W fixedly secured in position by the set-screw w , see Fig. 1, and having its upper end offset at w' . The inner face of the offset portion w' of the 120 arm W is formed with a shoulder w^2 adapted to serve as a detent to engage a corresponding shoulder w^3 on the curved arm W'. The arm W' has its hub w^4 mounted on a bearing a^9 , extending from a lug a^{10} formed 125

on the top of the arch a^2 of the frame A, and is held in place by the washer w^5 and screw w^6 . The lug a^{10} is counterbored around the bearing a^9 to form a pocket a^{11} 5 for a coiled spring w^7 which encircles the bearing. One end of the spring w^7 engages a hole a^{12} in the lug a^{10} and the opposite end is carried through a transverse hole w^8 in the hub w^4 of the arm W'. The torsion of the spring w^7 tends to rock the arm W' in the direction indicated by the arrow 2, Fig. 3, to hold its detent shoulder w^9 in engagement with the shoulder w^2 of the arm W. When the rod T is rocked slightly in the 10 direction indicated by the arrow 3, Fig. 3, the detent shoulders are disengaged and the force of the spring w^7 will move the arm W' upward. The lower end w^9 of the arm W' will then ride on the face w^{10} of the arm W 15 and force the latter outward to carry the rod T still farther downward in the direction indicated by the arrow 3. This latter movement of the arm W' as it swings the rod T downward carries the inner beveled end j' of 20 the clutch-lever J against the beveled face g^5 of the flange g' on the clutch-member G, to withdraw the latter from engagement with the teeth b^2 on the end of the spindle B. The disengagement of the detent shoulders 25 25 of the arms W and W' may be effected manually by movement of the handle T² and the stopping of the cop-driver is accomplished through such disengagement.

Automatic release of the detents is effected 30 by the means now described: Mounted on the inner end of the rod T is an arm 6 secured fixedly thereto by a set-screw 7. A pin 8 is driven through a hub 9 at the top of the arm and its opposite ends serve as bearings for a pivoted lever 10. Preferably, the lever 10 is formed of wire bent in U-shape with its ends curled around the ends of the pin 8 and its lower cross-bar 11 adapted to engage with the teeth 12 of a wheel 13 35 mounted on the winding-spindle B. The wheel 13 is fixedly secured to the spindle B by means of the set-screw 13^a and rotates therewith in the direction indicated by the arrow 4, see Fig. 3. Normally the cross-bar 40 45 50 55 60 65 70 75 80 85 90 95 100 105 110 115 120 125 130 lies out of range of the teeth 12 on the wheel 13, but the lever 10 is arranged to be carried upward into the position illustrated in Fig. 3 by means of a crank-arm 14, formed by an extension of the wire of one side of the lever, see Fig. 1. The lever 10 also has another extension or tail-piece 15 arranged below the wheel 13 and adapted to engage the latter in the space 16 between the two rows of teeth 12 so that when the end of the lever 80 is engaged with the teeth on the wheel it will not be carried upward thereby beyond its proper range of action, see Fig. 3.

The lever 10 is operated through the crank-arm 14 by means of a lever 17, preferably 85 formed of sheet-metal, and pivoted on the

boss a^8 which projects from the side of the frame A. The forward end of the lever 17 is provided with a slot 18 with which the end of the crank-arm 14 engages and its rear end 19 is curved downward and provided with an arcuate slot 20. With the lever 17 in its normal position, as illustrated in Fig. 2, the slot 20 is concentric with the axis of the rod L on which the traverse-frame M swings, and the slot 18 is so related to the axis of the lever 10 that the latter is held downward with its end out of range of the teeth 12 on the wheel 13. When the forward end of the lever 17 is lifted the slot 18 operates on the end of the crank-arm 14 to raise the lever 10 into engagement with the wheel 13 and this upward movement is effected through a spring 21. The spring 21 is arranged on the inside of the upright a' of the frame A with one end hooked through a hole a^{13} in a lug a^{14} on the frame and the other end secured to an ear 22 bent over from the forward end of the lever 17. The lever 17 is maintained in its normal position as illustrated in Fig. 2 by means of an end-stop-bar 90 or lever 23. Pivoted in the ears 24, 24 on the back of the traverse-frame M is a rod 25 having its inner end bent in the form of a crank-arm 26. Secured to the bar at a point substantially midway of its ends is a lever 27 having its lower end bent around the rod and clamped by a screw 28. Adapted to slide in the slotted, upper end of the lever 27 is an extension 29 secured to the main lever by the screw 30. The extension 29 is 100 preferably constructed of relatively thin, spring-metal and carries a thread-eye or guide 31 at its upper end. This construction of the end-stop-lever provides for a slight yielding of the extension 29 to allow for variations in the tension of the yarn y which draws through the guide 31, and the resilience of the lever can be varied through regulating the operative length of the extension by adjusting it up and down on the 105 lever 27. The lever 27 is normally held in a vertical position, as illustrated in Fig. 2, by the tension of the yarn y as it leads through the thread-eye 31 and is drawn down to the cop-tube x . When the tension 110 on the yarn is relieved, through breaking or exhaustion of the supply, the lever 27 is free to move outward into the position illustrated in Fig. 3 to allow the lever 17 to be rocked under the influence of its spring 21. 115

Mounted on the rod T on the outside of the frame A is an arm 32, secured by the set-screw 33 and having a screw 34 extending through its upper end in the direction of the cop-tube. The screw 34 may be slid through 120 its bearing in the arm 32 but is prevented from turning therein by a pin 35 engaging a longitudinal slot 36 in the top of the screw. Two check nuts 37, 37, on either side of the arm 32 serve to hold the screw 34 in its ad- 125 130

justed position. At the inner end of the screw 34 is pendulously supported on the pin 38 a cam-shaped button 39 which normally hangs in the position illustrated in Fig. 2, with its curved face downward and the point thereon nearest to the pivot 38 adjacent the cop-tube α . The button 39 is adapted to be engaged by the periphery of the cop when the latter reaches its predetermined diameter to move the arm 32 to bring the stopping mechanism of the machine into action as more fully described hereinafter.

The operation of the whole machine is as follows: The cop-tube or quill α is placed in position by mounting its end on the end of the support or spindle e^3 , and the bushing e^4 in which the spindle rotates is then pressed back against its spring a sufficient distance to allow the other end of the tube to be mounted on the end of the cop-driver F with the key f^3 engaging the transverse slot in the tube. The thread or yarn y is then drawn down from its source of supply, generally arranged above the machine, but not here shown, and led through the eye 31 on the lever 23. From the eye 31 the thread is carried across the edge of the curved top m^3 of the frame M and thence to the cop-tube α to which its end is secured.

No provision is made in the present invention for arresting the reciprocation of the thread-guide during the operation of the machine, the relative slow movement of the guide being continuous as imparted by the continuously oscillating rock-shaft C which is connected to the thread-guides of the whole series of heads. The winding-spindles B are also rotated continuously from the common source of power at the end of the gang of units, but each individual cop-driver may be stopped and started at the will of the operator, or automatically through the operation of its appropriate controlling mechanism. Previous to the start of the winding the cop-driver F is at rest with the clutch-lever J engaging the flange g' of the clutch-member G to hold its teeth g^2 out of engagement with the teeth b^2 on the spindle B. To start the winding operation the handle T^2 is moved to throw the rod T upward in the direction opposite to that indicated by the arrow 3, Fig. 3, and the clutch-lever J swings downward away from the flange g' on the clutch-member G. This allows the latter to slide on the clutch-driver F to bring its teeth g^2 into engagement with the teeth b^2 on the spindle B and the spindle and driver then rotate as one to impart rotation to the cop-tube α . The movement of the handle T^2 , as above described, carries the detent-shoulder w^2 of the arm W into engagement with the shoulder w^3 on the arm W' and the parts are held thereby to continue the winding operation of the machine.

The parts are now in the positions illus-

trated in Fig. 2 with the curved arm u of the lever U depressed to hold the upper end of the wire member V away from the pin o' on the bail O. This allows the bail O to hang free with its longitudinally-extending portion away from the yarn y and as the thread-guide N reciprocates back and forth along the traverse-frame M the rounded edge of the guide-button n will ride in under the yarn and pick it up in the guide-slot n^3 . After the thread has been thus automatically picked up by the guide the reciprocation of the latter will traverse it on the cop-tube to wind it in cross-helices or coils in the manner now well known to those versed in the art.

The upright position of the lever 23, maintained by the tension of the yarn y drawing through the eye 31, holds the lever 17 with its rear end 19 raised against the action of the spring 21. The slot 18 in its forward end, through engagement with the crank-arm 14, maintains the end of the lever 10 away from the toothed wheel 13 and with the parts in this position the crank-arm 26 is free to slide in the slot 20 as the traverse-frame M swings backward to allow for the increase in diameter of the winding. Should the yarn y become broken, however, or its tension be relieved through exhaustion of the supply, the lever 23 will be released and allow the lever 17 to rock under action of its spring 21, as illustrated in Fig. 3. This rocking movement of the lever 17 acts to raise the crank-arm 14 to throw the end of the lever 10 upward into engagement with the teeth 12 on the wheel 13 and such engagement will force the arm W outward to release the detent shoulders w^2 and w^3 . The disengagement of the detents allows the arm W' to swing upward under action of its spring w^7 so that the arm W is forced still farther outward and the rod T moved downward thereby. The movement of the rod T downward carries the clutch-lever J into engagement with the clutch-member G to slide the latter and arrest the rotation of the cop-driver F. As the rod T moves downward the inner end of the lever U is swung upward and acts to raise the member V to swing the bail O outward as before explained. This lifts the yarn out of the notch in the thread-guide N, as shown in Fig. 6, and prevents the guide from carrying the yarn back and forth in its reciprocation.

The machine is stopped at the completion of the cop by engagement of its periphery with the button 39 at the end of the screw 34. The screw 34 is adjusted in accordance with the required diameter of the cop and as the latter reaches this diameter its surface will contact with the inner end of the button 39 and turn the latter upward with the cam face riding on the cop. This causes the arm 32 to be forced outward to rock the rod T

downward and actuate the stopping-mechanism as before explained.

It will be seen that various other modifications might be made in the form and structure of the mechanism without departing from the spirit or scope of the invention, therefore, without limiting myself to the exact embodiment shown and described,

What I claim is:—

10. 1. In a winding machine, the combination with a rotating cop-driver, of a reciprocating thread-guide adapted to traverse the yarn on the cop, a traverse-frame for supporting said guide to move away from the axis of the cop with the increase in diameter of the winding, a thread-bail pivoted on the traverse-frame and extending adjacent the path of traverse of the guide, and means to rock said bail to disengage the yarn from 15 the thread guide during the reciprocation of the latter.

2. In a winding machine, the combination with a rotating cop-driver, of stopping-mechanism to arrest the rotation of the cop-driver, a reciprocating thread-guide, a traverse-frame for supporting the guide to move away from the axis of the cop as the latter increases in diameter, a thread-bail mounted on said frame adjacent the thread-guide, a sliding member adapted to move the bail to disengage the yarn from the thread-guide, and a lever connected with the stopping-mechanism and engaging the sliding-member to allow the movement of the latter with the traverse-frame, said lever adapted to be rocked to move the sliding-member to operate the thread-bail.

3. In a winding machine, the combination with the cop-driver, of stopping-mechanism therefor, a swinging traverse-frame, a thread-guide adapted to slide in said frame, a thread-bail pivoted on the frame and adapted to swing to disengage the yarn from the thread-guide, a wire-member mounted 40 to slide in the traverse-frame to engage the thread-bail to swing the latter, and a lever connected with the stopping-mechanism and formed with a slot engaging a right-angled portion of the wire-member to move the latter when the lever is rocked by the operation of the stopping-mechanism.

4. In a winding machine, the combination with a rotating cop-driver, of stopping-mechanism therefor, a reciprocating thread-guide for traversing the yarn on the cop, a traverse-frame for supporting said guide to move away from the axis of the cop with the increase in diameter of the latter, an end-stop-lever mounted on the traverse-frame and supported in its normal position by the tension of the yarn leading to the thread-guide, and means actuated to operate the stopping-mechanism when said lever is released by the breaking or exhausting of 55 the yarn.

5. In a winding machine, the combination with a rotating cop-driver, of stopping-mechanism therefor, a reciprocating thread-guide, a traverse-frame for supporting said guide to move away from the axis of the cop in accordance with the growth of the latter, an end-stop-lever pivoted on the traverse-frame and adapted to be supported in an upright position by the tension of the yarn drawing through it, a lever adapted to be 70 rocked to cause the operation of the stopping-mechanism, means to rock said lever, and a crank-arm on the end-stop-lever adapted to normally restrain the aforementioned lever from rocking but to allow it to 75 rock upon the breaking or exhausting of the yarn.

6. In a winding machine, the combination with a rotating cop-driver, of stopping-mechanism therefor, a reciprocating thread-guide, a swinging traverse-frame for supporting said guide to move away from the axis of the cop, an end-stop-lever pivoted on the frame and adapted to be supported by the tension of the yarn, a lever adapted 80 to be rocked to cause the operation of the stopping-mechanism, said lever formed with an arcuate portion concentric with the axis of the traverse-frame, means to rock said lever and a crank-arm on the end-stop-lever adapted to engage said arcuate portion of the aforesaid lever to normally restrain it 85 from rocking while the end-stop-lever is supported by the yarn.

7. In a winding machine, the combination with the stopping-mechanism therefor, of means to cause the operation of the stopping-mechanism, a rockable end-stop lever for controlling said means, said lever comprising a pivoted, non-flexible portion and a resilient extension formed of flat spring-metal mounted on the lever to slide longitudinally thereof, and clamping means to secure said extension on the lever at different distances from the pivot of the latter to 100 adjust the resilience of the extension.

8. In a winding machine, the combination with the winding-spindle, of a rod supported parallel therewith, a thread-guide slidable on said rod, means to reciprocate the thread-guide on the rod, a traverse-frame pivoted on said rod and adapted to direct the traverse of the thread-guide to allow it to move outward from the axis of the winding-spindle as the cop increases in diameter, and means to resist the movement of the guide toward the axis of the winding-spindle.

9. In a winding machine, the combination with the winding-spindle, of a rod supported parallel therewith, a thread-guide pivotally and slidably mounted on the rod, an oscillating rocker-arm, means to connect the arm with the thread-guide to reciprocate the latter, a traverse-frame pivoted on 125 the rod.

the rod and adapted to direct the traverse of the thread-guide to allow it to move outward from the winding-spindle, dogging means fixedly secured in relation to the 5 winding-spindle, and a dog-lever mounted on the traverse-frame and engaging said dogging means to normally prevent the movement of the guide toward the axis of the winding-spindle.

10 10. In a winding machine, the combination with the frame, of a winding-spindle mounted to rotate in bearings on the frame and formed with an axial bore at its end, a thread-guide adapted to be reciprocated 15 with respect to the winding-spindle, means to reciprocate said guide, a cop-driver rotatable in the bore of the spindle and extending axially therefrom, a sleeve slidable longitudinally on the cop-driver and formed 20 with a flange, means to connect the sleeve rotatively with the cop-driver, means to engage the sleeve with the winding-spindle to cause the cop-driver to be rotated thereby, and a lever adapted to engage the flange on 25 the sleeve to disengage the latter from the spindle.

11. In a winding machine, the combination with a rotating winding-spindle formed with an axial bore and radial teeth at its 30 end, of a thread-guide adapted to be reciprocated with respect to the winding-spindle, means to reciprocate said guide; a cop-driver rotatable in said bore and projecting axially therefrom, a sleeve slidable on the 35 cop-driver and formed with teeth adapted to engage the teeth on the end of the spindle, means to secure the sleeve rotatively with the cop-driver, resilient means to slide the sleeve into engagement with the spindle, and 40 a lever adapted to engage the sleeve to disengage it from the spindle.

12. In a winding machine, the combination with a rotating winding-spindle formed with an axial bore at its end, of a thread-guide adapted to be reciprocated with respect to the winding-spindle, means to reciprocate said guide; a cop-driver mounted rotatably in said bore, a sleeve slidable on the cop-driver and having means to engage 50 the end of the spindle, said sleeve formed with a tapered flange, means to secure the sleeve rotatively with the cop-driver, a spring to normally hold the sleeve in engagement with the spindle, and means engaging the flange on the sleeve to slide the latter to disengage it from the spindle.

13. In a winding machine, the combination with a rotating winding-spindle formed with an axial bore, of a thread-guide adapted to be reciprocated with respect to the winding-spindle, means to reciprocate said guide; a cop-driver rotatable within said bore and projecting therefrom, a flange on said cop-driver, a bearing for the end of the 65 cop-driver arranged to take the end thrust

against the flange, a sleeve rotatively secured to the cop-driver and slidable thereon, said sleeve formed with a tapered flange, means on the sleeve to engage the end of the spindle, a spring arranged between the flange on the cop-driver and the end of the sleeve to slide the latter into engagement with the spindle, and means adapted to engage the side of the flange on the sleeve to slide the latter and disengage it from the spindle. 70

14. In a winding machine, the combination with a rotating winding-spindle formed with an axial bore at its end, of a thread-guide adapted to be reciprocated with respect to the winding-spindle, means to reciprocate said guide; a cop-driver rotatably mounted in said bore and projecting therefrom, a flange on said cop-driver, a sleeve slidable on the cop-driver, means on the 80 sleeve for engaging the end of the spindle, a pin projecting through the cop-driver and engaging slots in the sleeve, a flange on the sleeve formed with a beveled face, a spring arranged between said flange and the flange 85 on the cop-driver, a ball-bearing adapted to support the end of the cop-driver and take the thrust of the spring against the flange, and a lever adapted to engage the beveled face of the flange on the sleeve to 90 slide the latter against the action of the spring to disengage the sleeve from the spindle. 95

15. In a winding machine, the combination with a constantly reciprocating thread-guide, of a constantly rotating spindle, a cop-driver adapted to be connected with the end of said spindle to be rotated therefrom, stopping-mechanism to arrest the rotation of the cop-driver, and means to engage the yarn to 100 carry it away from the thread-guide upon the arrest of rotation of the cop-driver. 105

16. In a winding machine, the combination with a constantly reciprocating thread-guide, of a constantly rotating spindle, a cop-driver connected to the end of said spindle to be rotated therefrom, stopping-mechanism to disconnect said cop-driver from the spindle, means to cause the operation of said stopping-mechanism upon the 110 breakage or exhaustion of the yarn, means to cause the operation of the stopping-mechanism when the cop reaches a predetermined diameter, and means to disengage the yarn from the thread-guide during the operation 115 of the stopping-mechanism. 120

17. In a winding machine, the combination with a frame A, of a winding-spindle B rotating in bearings on the frame, a cop-driver F, a clutch-member G to connect the cop-driver with the winding-spindle, a rod D supported in the frame parallel with the winding-spindle, a rod T supported from the rod D to swing about on its axis, a clutch-lever J on said rod T adapted to 125 op- 130

- erate the clutch-member G, an arm W' pivoted on the frame A and formed with a detent w^3 , an arm W secured to the rod T and formed with a detent adapted to engage the 5 detent w^2 , a handle T² to swing the rod T to disengage the detents, and a spring to rock the arm W upon the release of the detents to cause it to move the arm W and swing the rod T to operate the clutch-lever.
- 10 18. In a winding machine, the combination with the winding-spindle B, of a cop-driver F rotated thereby, a clutch-member G to connect the cop-driver with the spindle, a fixed rod D, a rod T supported to swing 15 about the axis of the rod D, a clutch-lever J mounted on the rod T and adapted to be moved thereby to operate the clutch-member, and means to swing the rod T.
19. In a winding machine, the combination 20 with the winding-spindle, of a cop-driver, a clutch-member to connect the cop-driver rotatively with the winding-spindle, a fixed rod D arranged parallel with the winding-spindle, a rod T pivoted to swing on the rod D, detent arms to maintain the rod 25 T from swinging, a toothed wheel on the winding-spindle, means mounted on the rod

T and adapted to be engaged by said wheel to release the detents, and a clutch-lever mounted on the rod T and moved thereby 30 upon the release of the detents to operate the clutch-member.

20. In a winding-machine, the combination with the winding-spindle, of a cop-driver rotated thereby, stopping-mechanism 35 to arrest the rotation of the cop-driver, detents to prevent the operation of the stopping-mechanism, a wheel 13 on the winding-spindle, a lever 10 connected to disengage the detents when engaged by the wheel, a lever 17 to operate the lever 10, an end-stop-lever 23 formed with a crank-arm engaging the lever 17 to normally prevent its movement and means to operate the lever 17 to move the lever 10 when the end-stop-lever 40 is released by the breakage or exhaustion of the yarn.

In testimony whereof I affix my signature in presence of two witnesses.

CLAES RYDEN.
